UNITED STATES PATENT OFFICE

2,522,383

CAN OPENER

Josef Lampl, Los Angeles, Calif., assignor to National Machine Engineers, Los Angeles, Calif., a corporation of California

Application September 23, 1946, Serial No. 698,826

7 Claims. (Cl. 30—9)

1

This invention relates to can openers and more particularly to improvements in can openers of the semi-automatic type wherein a gripping and cutting mechanism is automatically operable or releasable by the appropriate movement of an operating handle.

The instant application is based upon a can opener having many of the basic structural features disclosed in my co-pending United States patent application for Can Opener, Serial No. 597,176, filed June 2, 1945, and is a continuation in part of said application. In said co-pending application the initial rotation of an operating handle in a given direction actuates an appropriate mechanism, and causes a primary engagement of the lip of a can between a suitably serrated roller and a cutter, while a further rotation of the handle in the same direction operates to shear the lid from a can. On the other hand, rotation of said handle in a reverse direction initially operates said mechanism to move the serrated wheel and cutter apart in a manner to release the lip of the can from its cutting engagement therebetween.

The mechanism above referred to and described hereinafter generally comprises a full gear rotatably secured to the operating handle and a mutilated gear positioned to mesh with the full gear during the initial phase of the rotation of the handle and full gear in either a driving or releasing direction. The handle is directly connected with the serrated roller while the mutilated gear is indirectly connected to the serrated wheel through an eccentric bearing and lever which initially operate to raise and lower the serrated wheel relative to the cutter depending upon the direction of rotation of the driving handle.

It is intended in the instant invention to provide certain improvements for application to a can opener of the general type disclosed in said co-pending application or to can openers utilizing equivalent devices to perform the same functions. These improvements are intended to ease the operation of the can opener and, among other things, to furnish a plurality of resilient connections between the can and the operative can-engaging mechanism of the can opener.

It frequently occurs in can openers of conventional construction that the cutting and gripping faces are rigidly mounted in an unyielding manner so that a can intended to be operated upon must be more or less accurately and positively positioned between the cutting and driving members. But even after such an exact

2

positioning of the can, the cutting and driving elements tend to jam and stick against the can bead or cause the can to tilt, largely due to irregularities in the can surfaces and the lack of adequate compensation for these conditions in the can opener.

It is therefore an object of this invention to provide, in a can opener of the character described, a driving wheel mounted for yieldable can-cutting movement in a vertical direction.

It is another object to provide a new and improved mounting for a serrated driving wheel by means of which said wheel is yieldable laterally during a can-cutting operation.

15 A further object is to provide a new and improved can opener in which both the cutting and driving elements are yieldably mounted for movement in a vertical as well as a horizontal direction so as to provide a substantially "floating" can-cutting apparatus.

20 Another object is to provide a new and improved can opener of the desired character described in which a cutting wheel is resiliently mounted for relative axial or wobbling movement with respect to its associated apparatus.

25 It is a further object to provide a can opener of new and improved construction characterized by simplicity of construction and ease of use and especially intended for use in connection with the mechanism illustrated and described in my co-pending application as herein set forth.

30 A still further object is to provide a new and improved substantially fool-proof means adaptable for the yieldable accommodation of cans of any conventional size and designed to prevent sticking or jamming of the cutting parts or undue tilting of the can.

35 Another further object is to provide a can opener having new and improved self-aligning features and which is susceptible of economical reproduction by conventional mass production methods.

40 Other objects and advantages will appear and be brought out more fully from the following description considered with reference to the accompanying drawings throughout which like parts are designated by like numerals.

In the drawings:

45 Figure 1 is an elevational view of a can opener embodying this invention illustrating the side upon which the cutting parts are located and showing these parts in an open position.

50 Figure 2 is an elevational view of the can opener taken from the opposite side of Figure 1, parts being cut away.

3

Figure 3 is a view similar to Figure 2 with the parts disposed in another operative position.

Figure 4 is a vertical, sectional view on the line 4—4 of Figure 1.

Figure 5 is a view similar to Figure 1, parts of the supporting bracket being cut away and the handle and operative parts being shown in a closed or can-cutting position.

Figure 6 is a fragmentary, detailed view of the cutter and its mounting.

Figure 7 is a detailed sectional elevational view on the line 7—7 of Figure 1.

Figure 8 is a plan sectional view on the line 8—8 of Figure 1.

Figure 9 is a vertical sectional view on the line 9—9 of Figure 1.

Referring more particularly to the drawings, I show an elongated can opener frame 11 pivotally mounted by means of pins 12 to a wall bracket 13 which may be secured to a wall 14, as by means of screws 15. Said frame has a cutout portion 16 providing an upper leg 17 and a lower leg 18 which may be bent into bearing sleeves 12' for engagement with the pins 12 so as to provide a sturdy vertical pivotal support for the can opener. Said frame is further provided with a fixed shouldered pin 19, a hole 20 for the orbital oscillation of a shaft 21, and circular hole 22 between said pin 19 and said hole 20 for rotatable confinement of an annular eccentric disk 23 as hereinafter more fully appears. An ear 24 on said frame 11 extends upwardly at an angle to the plane of said frame and provides a fixed support for a freely rotating cutting wheel 26, while flanges 27, and 29, stuck out from the frame, serve to strengthen it. The flanges 27 and 29 also serve, in cooperation with resilient structures hereinafter described, as can-positioning guides to hold a can in correct alignment with the cutting wheel 26. An optional hook bottle opener 30 may be formed in the lower portion of the frame.

A lever 31 is oscillatably mounted at one of its ends on the pin 19 through a slot 32 in said lever 31. Said lever 31 is further journaled between its ends upon an eccentric bearing pin 33 affixed to the eccentric disk 23 rotatably mounted in the frame 11 so that the rotation of said disk 23 imparts an orbital up-and-down motion to the right-hand end of the lever 31, as best illustrated in Figures 1 and 5. The movement of the lever 31 resembles that of a connecting rod between a piston and crankshaft in an engine but is restricted, for reasons which will hereafter appear, to less than a complete revolution of the disk 23.

A handle 34 is mounted upon a crank 35 keyed to the shaft 21. Said shaft 21 is rotatably mounted in the right-hand end of said lever 31 and extends through the hole 20 for orbital rotation therein. Keyed to the shaft 21, in addition to the crank 35, is a full gear 36, a cam 37 and a serrated

Eccentrically and rigidly affixed to said eccentric disk 23 is a mutilated gear 39 adapted to mesh with the full gear 36 during certain operating cycles.

It will now appear that the rotation of the crank 35 in either direction will, if said gears 36 and 39 are in mesh, cause the mutilated gear 39 and the eccentric disk 23 to rotate, thereby rotating the eccentric bearing pin 33 and oscillating the lever 31 so as to orbitally raise or lower the shaft 21 within the hole 20. The mutilated gear 39, being eccentrically mounted upon the eccentric disk 23, in like manner to the lever 31, oscillates in unison with the lever 31 and thereby

4

retains a substantially fixed center-to-center relationship to the full gear 36 which is carried by the lever 31.

The cutting wheel 26 is rotatably mounted on a stud 40 seated in the ear 24 of the frame 11 at an angle with respect to the plane of the serrated wheel 38, and with the cutting edge 41 of the cutting wheel 26 adjacent to the outer edge of said serrated wheel 38 when the serrated wheel 10 is in its uppermost position.

Pivottally mounted upon the mutilated gear 39 (Figures 2 and 3) by means of a pin 42, I provide a pawl 43. A spring 44 is mounted in a slotted pin 45 also on the gear 39 against which pin one end 46 of the pawl is normally urged by the spring. The other end 47 of the pawl projects beyond the teeth at one end of the mutilated gear 39. At the other end of the mutilated gear 20 I provide an enlarged tooth or stop 48 which prevents the clockwise rotation of the mutilated gear or the counter-clockwise rotation of the full gear beyond their position shown in Figure 2. A stop 25 49 is secured in the frame 11 diametrically opposite the position of the enlarged tooth 48 shown in Figure 2 for limiting the counter-clockwise rotation of the mutilated gear by the engagement of said enlarged tooth 48 with said stop 49, as shown in Figure 3.

The cam 37, which is keyed to the shaft 21, lies 30 in the plane of the pawl 43 so that a clockwise rotation of the handle 34 (Figure 2) initially causes the mutilated gear 39 to run off of the full gear 36, and subsequently causes the cam 37 to engage the back 50 of the pawl and to flex the 35 spring 44 thereby permitting the cam 37 to slip past said pawl 43 at each successive clockwise revolution of the crank. The enlarged tooth 48 meanwhile holds the mutilated gear 39 against further counter-clockwise rotation due to the 40 engagement of said tooth with the stop 49.

A counter-clockwise rotation of the crank turns the full gear 36 and hence the cam 37 into the position shown in Figure 3 wherein the cam face 51 has engaged the end 47 of the pawl. 35 Continued counter-clockwise rotation of the crank brings about an inter-engagement of the gears 36 and 39 and a clockwise rotation of the mutilated gear 39 until the enlarged tooth 48 on said mutilated gear engages the full gear 36 50 thereby preventing further clockwise rotation of said mutilated gear (Figure 2).

A cover 52, of a size and shape suitable for covering the gears 36 and 39 and their associated mechanism, may be provided upon the 55 side of the frame opposite from the serrated wheel 38 to protect the gears, the cam 37, and the pawl 43, and to avoid possible injury to the fingers of an operator. Said cover 52 has a hole (not shown) to accommodate the shaft 21. A 60 thrust washer 54 for the crank 35 preferably is provided between said cover and said crank. The cover 52 may be secured to the frame 11 as by screws 55.

To removably secure the frame 11 on the pins 65 12, I provide a hook-shaped latch 56 pivoted to the frame 11 by a pin 57. Said latch may engage a slot 58 formed in an ear of the bracket 13 whereby the frame 11 is adjustably held in a desired position of extension from the wall 14 70 and also may be releasably locked against vertical movement upon said pins 12. A finger-piece 59 aids the manipulation of said latch 56. The frame 11 may be swung parallel with the wall 14 when said latch 56 is released from engagement with the slot 58.

The axes of the cutting wheel pin and the driving wheel pin or shaft are preferably inclined toward one another at approximately 30° included angle, but at least greater than 0° and not more than about 45°.

The parts and their relationship described up to this point are similar to those in my application, Serial No. 597,176, and for continuity, and to render easier an understanding of the improvements to which the present application is particularly directed, I will next describe the operation of the device as thus far set forth.

The handle 34 is turned to its limit of counter-clockwise rotation as shown in Figure 2, thus bringing the enlarged tooth 48 of the mutilated gear 39 into engagement with the full gear 36 and preventing further counter-clockwise rotation of said full gear as above stated. In this position the serrated wheel 38 is spaced from the cutting wheel 26 permitting the insertion of the lip of a can therebetween, while the top and side of the can may be held against the flanges 27 and 29, and the eccentric bearing pin 33 is at the lower limit of its movement.

The handle 34 is next turned in a clockwise direction from the position illustrated in Figure 2, resulting in the rotation of the mutilated gear 39 in a counter-clockwise direction until the cutting wheel 26 and the serrated wheel 38 are in can-cutting position, whereupon said mutilated gear runs off the full gear 36, just as the enlarged tooth 48 engages the stop 49 to prevent the continued counter-clockwise rotation of said mutilated gear. Continued clockwise rotation of the handle rotates the serrated wheel 38 which carries the edge of the can with it for cutting engagement with said cutting wheel 26. At each successive clockwise rotation of the handle 34 the cam 37 slips by the back 52 of the pawl 43 by depressing the spring 44 in a counter-clockwise direction.

Upon completion of the cutting operation, the lid having been severed from the can, the handle is given a counter-clockwise rotation as heretofore described, resulting in the spacing of the serrated wheel 38 from the cutting wheel 26, whereby the lip of the can is released.

Just before the lid of the can is completely severed, said lid is tilted upwardly so as to be readily grasped by virtue of the novel relationship between the cutting edge 41 of the wheel 26 and the serrated wheel 38. The cutting wheel 26 is disposed at an angle to the plane of the serrated wheel 38 as hereinbefore noted. The axis of the cutting wheel is preferably offset slightly from that of the serrated wheel when the latter is in cutting position. By this arrangement the cutting edge 41 bears down upon the top of the can lid adjacent to the cutting area slightly rearwardly of the tangential contact of the can lip with the serrated wheel. The edge of the lid is thereby pushed downwardly by the inclined faces of the cutting edge 41 tending to tilt the lid upwardly so that it may be readily grasped before the completion of the cutting operation. The cutting wheel 26 should have sufficient thickness and the angle of the cutting edge should be sufficiently great to prevent the jamming and binding of the cutting wheel during the cutting operation. The proportions illustrated have been found satisfactory.

It should be noted that the movement of the serrated wheel 38 towards the cutting wheel 26, in the initial clockwise rotation of the crank 35, is not a straight-line but a curved-line move-

ment, wherein the serrated wheel is swung upwardly towards the cutting wheel at the same time the serrated wheel is turning, thereby gripping the under side of the can lip and moving the can into operative proximity to the cutting wheel. The resultant of these curved-line and rolling movements is a smooth, progressive, initial can-piercing operation which is achieved by a minimum of effort.

10 Thus far this description has been concerned with the basic form of my can opener essentially as shown and described in the co-pending application hereinabove referred to. The improvements comprising the subject matter of the instant application broadly comprise a spring generally designated by the numeral 100 and its associated structure, an offset spring-like section 200 in the lever 31, a spring 300 associated with the cutting wheel 26 including its cooperating structures, and a spring guide 400, as will now be described in greater detail.

15 Referring first to the spring modification 100 associated with the lever 31, said lever is formed with a slot 32, as above noted, such that the pin 19 can move longitudinally therein. In utilizing the spring 100 said slot is made substantially wider than the shank of the pin 19 thereby permitting a predetermined degree of vertical tilting movement of the lever on the bearing pin 33. To this end, the frame may be formed with an outwardly extending ear 101 having a downwardly extending lug 102, and the corresponding upper edge of the lever may be similarly formed with an upwardly extending lug 103. The spring 100 encircles these two lugs and is normally held in a condition of compression therebetween in such a manner that the left-hand end of the lever 31, as illustrated in Figures 1 and 5, is normally forced downwardly to hold the uppermost edge 104 of the slot against the pin 19. Therefore, a downward pressure upon the serrated wheel acting to remove the same away from the cutting wheel will be required to further compress the coil spring 100. Such a movement may occur whenever the cutting lip of a can has an increased vertical thickness or similar irregularity. The tension of the spring 100 may be so adjusted that the normal cutting operation of the can opener may be carried out with the spring in its extended position normally forcing the upper edge 104 of the slot against the pin 19 and so that only the exceptional strain or stress of a vertically thickened seam will serve to further compress the spring 100 or force the bottom edge 105 of the slot towards the shank of the pin 19. In a properly proportioned can opener, the bottom edge of the slot should never quite engage the pin 19 during a can-cutting operation.

20 Referring now to the spring form of the lever 31, an offset generally designated by the numeral 200 may be formed as by a double bend or by a simple kick to properly space the right-hand end of the lever carrying the serrated wheel outwardly from the plane of the body of the can opener, preferably though not necessarily at an angle to the frame. The lever 31 is preferably made of spring steel or like material but if desired it may be tempered only at and adjacent the offset portion 200. This construction of the lever permits the serrated wheel 38 to move horizontally away from the cutting wheel as when the lip of a can contains any transverse thickening or irregularity such as a transversely thickened bead or seam. Normally the lever is spaced from the frame to

retain the serrated and cutting wheels axially apart a distance approximately equal to a double thickness of the material of which the can is made so as to approximate the thickness of a can lip in which no abnormal thickening exists. It is within the contemplation of this invention, however, normally to position the serrated wheel substantially against the inner cutting edge 291 of the cutting wheel so that any conventional can lip is pinched between the cutter and the serrated wheel while being cut. It will be seen, therefore, that this latter construction of the lever provides the serrated wheel and the cutting wheel with a resilient tolerance in a horizontal direction in a manner to compensate for the irregularities in the lip of a can due to variations in its thickness. Moreover the combination of the springs 100 and 200 allow a can to "float" between the cutting and serrated wheels in a vertical as well as a horizontal direction.

The cutting wheel 26, as most clearly illustrated in Figure 6, is mounted upon a pin 402 optionally extending entirely therethrough and formed with a head 381 on the opposite side of the frame 24 from the said cutting wheel. On the end adjacent the frame 24 this pin is provided with a shoulder 302 which may be either loosely or fixedly associated with the pin by keying or pressing. An annular shoulder or washer 303 also encircles the pin and is spaced from the shoulder 302 so that the cutting wheel 26 may move axially or wobble upon its pin to a limited extent.

Coil spring 300 encircles the shoulder 302, the washer 303, and the shaft of the cutting wheel 26 and normally urges the cutting wheel axially away from the ear 24 of the frame upon which it is mounted. A certain amount of play is provided in the shaft of the cutting wheel so that the wheel is free to move to a limited extent laterally thereby providing a variable clearance between the cutting wheel and the serrated wheel 38. The purpose of the spring 300 is to hold the cutting wheel 26 in a normal position parallel to the ear 24 during the normal cutting operation, but to allow the cutting wheel to move slightly away from the serrated wheel during the time when the can opener is cutting through the thickened seam of a can, thereby providing greater clearance for the seam between the serrated wheel and the cutting wheel.

Adjacent the cutting wheel 26 and at a point upon the opposite side of said wheel from the guide 27 is a spring guide 400 as most clearly illustrated in Figures 1, 4, 5, and 9. The spring guide comprises a substantially inverted L-shaped member preferably formed of spring steel and secured to the frame by any suitable means such as rivets 401, and an outwardly extending leg 402 which functions in the manner of a vertically movable guide for the lip and top of a can. In view of the fact that cans of unusually large diameter, for example those having a capacity of one gallon or more, tend to be tipped out of the vertical during a cutting operation the cans tend to stick or jam between the cutting and serrated wheels. The abutment of the top of the can with the underside of the outwardly extending leg 402 is designed to yieldably resist such undesired tipping. Said leg is preferably given a downward slant in order to assist in guiding a can while retaining and urging the same into position against the serrated wheel and inwardly towards the frame at that

point. Such an action is found to improve and facilitate the cutting of the can.

By the addition of the springs 100, 200, 300 and 400, and the structures associated with them, the can may in a real sense be said to "float" during the entire cutting operation, inasmuch as it is permitted to have a yieldable vertical movement by virtue of the springs 100 and/or 300. Furthermore, the wobbling movement of the cutting wheel and also the lateral or axial movement of the serrated wheel due to the spring structure 200 incorporated in the lever permits resilient lateral movement of these parts and the spring guide 400 further permits a limited degree of deviation of the can from the vertical. Thus a suitable combination of these resilient structures insulates the entire operative mechanism as well as the can against shock and is nicely calculated to compensate for variations in thickness and proportions of the rim of such can. From the operator's point of view the can may easily be placed in a cutting position on the can opener without time-consuming adjustments and without being concerned over whether all parts are in proper relation to each other since all essential operative parts are substantially self-aligning. The handle has been found to revolve with a minimum of effort and a maximum of effectiveness.

While I have herein shown and described my invention in what I have conceived to be the most practical and preferred embodiment, it is recognized that departures may be made therefrom within the scope of my invention, which is not to be limited to the details disclosed herein but is to be accorded the full scope of the claims so as to embrace any and all equivalent devices.

Having thus described my invention, what I claim as new and desire to secure by Letters Patent is:

1. A can opener comprising a supporting frame, a cutter journaled upon the frame, a lever oscillatably mounted upon the frame, and a shaft rotatably mounted on the lever, a crank, a cam, a full gear and a driving wheel keyed to said shaft, an eccentric bearing oscillatably connecting said lever to said supporting frame, a mutilated gear operatively connected to said bearing and engageable with said full gear, a spring urged pawl pivotally mounted on said mutilated gear and engageable with said cam in one direction of rotation of said shaft initially to cause the engagement of said mutilated gear with said full gear, a stop on said mutilated gear, an extension on said supporting frame engageable by said stop to limit the rotation of said mutilated gear in one direction and said stop being also engageable with said full gear to limit the rotation of said mutilated gear in the opposite direction, and resilient means urging said driving wheel into a proximate relationship with said cutter.

2. A can opener comprising a supporting frame, a cutter journaled upon the frame, a lever oscillatably mounted upon the frame, and a shaft rotatably mounted on the lever, a crank, a cam, a full gear and a driving wheel keyed to said shaft, an eccentric bearing oscillatably connecting said lever to said supporting frame, a mutilated gear operatively connected to said bearing and engageable with said full gear, a spring urged pawl pivotally mounted on said mutilated gear and engageable with said cam in one direction of rotation of said shaft initially to cause the engagement of said mutilated gear with said full gear,

a stop on said mutilated gear, an extension on said supporting frame engageable by said stop to limit the rotation of said mutilated gear in one direction and said stop being also engageable with said full gear to limit the rotation of said mutilated gear in the opposite direction, and resilient means urging said driving wheel into a proximate relationship with said cutter, said lever having a spring action normally urging the driving wheel axially outwardly away from the frame and being offset in its body portion in a manner to carry the end of the lever most proximate to the cutter outwardly from, but substantially parallel to, the frame body.

3. A can opener comprising a supporting frame, a cutter journalled upon the frame, a lever oscillatably mounted upon the frame, and a shaft rotatably mounted on the lever, a crank, a cam, a full gear and a driving wheel keyed to said shaft, an eccentric bearing oscillatably connecting said lever to said supporting frame, a mutilated gear operatively connected to said bearing and engageable with said full gear, resilient guide means positioned adjacent the cutter adapted to yieldably hold the top of a can substantially level during a cutting operation.

4. In a can opener comprising a supporting frame, a cutter journalled upon the frame, a lever oscillatably mounted upon the frame, and a shaft rotatably mounted on the lever, a crank, a cam, a full gear and a driving wheel keyed to said shaft, an eccentric bearing oscillatably connecting said lever to said supporting frame, a mutilated gear operatively connected to said bearing and engageable with said full gear, spaced guide arms projecting laterally from said frame at both sides of the cutter, the novelty comprising at least one of said guides normally bearing downwardly upon the top of a can and being vertically flexible in a manner to yieldably hold the bead of the can against the driving wheel.

5. In a can opener of the character described comprising a driving wheel element and a cutter element operatively mounted on a frame for relative radial motion towards one another, said driving element being mounted inwardly closer to the frame than the cutter element, a lever journalled in the frame, said driving element being rotatably mounted on the lever, means for bringing the driving element and the cutter element into an operative, can-cutting position, the novelty comprising said lever having a spring normally urging the driving wheel axially outwardly away from the frame and against said cutter.

6. In a can opener of the character described comprising a driving wheel element and a cutter element operatively mounted on a frame for rel-

ative radial motion towards one another, said driving element being mounted inwardly closer to the frame than the cutter element, a lever journalled in the frame, said driving element being rotatably mounted on the lever, means for bringing the driving element and the cutter element into an operative, can-cutting position, the novelty comprising the journalled connection of the lever and the frame providing relative play in a vertical direction between the cutter and the driving wheel, and resilient means normally urging said driving wheel and said cutting wheel axially to an extreme of proximity limited by the play in said journalled connection.

7. In a can opener of the character described comprising a driving wheel and a rotative cutter operatively mounted on a frame for relative radial motion towards one another, the improvement comprising: a shaft having said cutter loosely journalled thereon, a first resilient means normally urging said cutter towards an end of said shaft outwardly from said frame, a stop limiting the axial movement of said cutter on said shaft, a lever mounted on said frame for relative longitudinal oscillatory movement, said driving wheel being rotatably mounted on said lever, a second resilient means associated with said lever normally urging said driving wheel outwardly from said frame and normally into a proximate can-cutting relationship with said cutter, a third resilient means associated with said lever adapted to tilt said lever with respect to said frame in a manner to urge said driving wheel radially towards said cutter, said lever having a loose journalled connection with said frame whereby said driving wheel element may be yieldably urged away from said cutter by said third resilient means to an extent limited, and a fourth resilient means extending outwardly from said frame adjacent the cutter adapted to yieldably press a can downwardly against the driving wheel during a cutting operation, all of said resilient means being cooperable to yieldably mount a can in cutting position on said can opener.
